(57) **CLAIM**

The ornamental design for a casing for LED lighting, as shown and described.

DESCRIPTION

FIG. 1 is a perspective view of my new design showing a casing for LED lighting;

FIG. 2 is a front elevation view thereof;

FIG. 3 is a side elevation view thereof;

FIG. 4 is a top plan view thereof;

FIG. 5 is a bottom plan view thereof; and,

FIG. 6 is another perspective view of my new design showing the casing for LED lighting.

The broken lines in the drawings depict portions of the casing for LED Lighting and form no part of the claimed design.
